UNITED STATES PATENT OFFICE.

FRANK A. HAUGH, OF INDEPENDENCE, KANSAS, ASSIGNOR TO ANNA B. BLOOM, OF INDEPENDENCE, KANSAS.

UNDERREAMER.

1,144,195.

Specification of Letters Patent. Patented June 22, 1915.

Application filed March 5, 1914. Serial No. 822,719.

To all whom it may concern:

Be it known that I, FRANK A. HAUGH, a citizen of the United States, residing at Independence, in the county of Montgomery and State of Kansas, have invented certain new and useful Improvements in Underreamers, of which the following is a specification.

This invention relates to new and useful 10 improvements in under-reamers, and has particular reference to that type of tools which are designed particularly for use in boring oil wells or Artesian wells.

The principal object of this invention is 15 to provide an under-reamer constructed with such regard to number, proportion and arrangement of parts that it may be cheaply manufactured, and will be durable and efficient in its action.

20 A further object is to provide an underreamer consisting essentially in a pair of co-acting bit members which are slidably mounted on the stock of the tool, and are adapted to be normally held in expanded 25 operative relation thereto by means of a spring-pressed head detachably connected to the lower terminal of the stock and disposed in recesses formed in the adjacent faces of the bits.

30 The above and additional objects are accomplished by such means as are illustrated in the accompanying drawings, described in the following specification, and then more particularly pointed out in the claims which 35 are appended hereto and form a part of this application.

With reference to the drawings, wherein 40 there has been illustrated the preferred embodiment of this invention as it is reduced to practice, and throughout the several views of which similar reference numerals 45 designate corresponding parts, Figure 1 is a side elevation of the reamer, showing the bits in operative expanded position; Fig. 2 is a side elevation, showing the bits in contracted inoperative position; Fig. 3 is a section on the line 3-3 of Fig. 2; Fig. 4 is a fragmentary vertical section, showing particularly the catch member which is employed in properly securing the spring between the bits; Fig. 5 is a perspective view showing the stock, expanding head, and bit members of the reamer in disassembled re-

lation indicating though the manner in which these elements are adapted to be assembled for co-operation; and Fig. 6 is a detail sectional view of the stock of the reamer taken on the line 6-6 of Fig. 5.

The preferred embodiment of the invention consists essentially in a pair of cutting 60 blades 10 and 11, which are mounted to embrace and slidably receive a stock 12, detachably secured to the lower terminal of which is an expanding head 13 adapted to engage in recesses 14 formed in the adjacent 65 faces of the bits for normally holding the lower cutting edges 15 in extended operative position.

The cutting blades or bits 10 and 11 are substantially identical in construction, and 70 it is deemed necessary, therefore, to describe only one of them in detail. Each of these blades or bit members is formed from an elongated metallic bar, preferably tempered steel, which is substantially semi-circular in 75 cross section and is cored out on its inner face to produce a recess 14 adjacent its lower terminal and a dove-tailed groove 16 adjacent its upper terminal. The recess 14 is adapted to receive the expanding head 13, 80 as has been previously explained, while the groove 16 is provided for the reception of a longitudinally extending rib which is formed on the stock 12, as will be herein-after fully described. The lower terminal 85 of each bit member is, as stated, provided with the outwardly directed cutting edges 15. While these cutting edges have been shown in the drawings, and in Fig. 5 thereof particularly, as being relatively blunt 90 and concave, it is obvious that the members 15 may be shaped to adapt the reamer for any class of work for which it may be employed.

The recess 14 is semi-circular in cross section for the greater part of its length, being formed at its upper terminal with a straight wall, as indicated at 17. The lower terminal of the recess 14 is, however, curved and rounded outwardly to merge into the flat 100 face 18 of the blade, as indicated at 19. The lower terminal of the recess 14 of each cutting blade or bit is thus formed so that the downward movement of the cylindrical expanding head 13 through the recesses will 105 cause a separation or spreading of the lower

terminals of the bits when the reamer has been inserted in the well casing and emerges from the lower terminal thereof. The groove 16 is provided with a flat horizontal 5 wall at its lower end, as indicated at 20, for a purpose to be hereinafter disclosed. Notches or recesses, indicated at 24 and 25, are cut into each side of the upper terminal of both blade members to receive the terminals of the connecting strips or plates 26. These connecting plates 26 are terminally 10 apertured to receive screws insertible in the apertures 27 which are formed in each of the notches 24 and 25 so that the blades or cutting bits may be properly secured in operative 15 assembled relation on the stock 12. This stock 12 is formed from a solid metallic bar, the upper end of which is shaped to produce a head 28 of conventional design, 20 and the lower end of which is reduced in cross section and is longitudinally chamfered on its four corners, producing, as in Fig. 6, the oppositely disposed longitudinally extending dove-tailed ribs 29 and 30, 25 and the shoulders 31 and 32 which extend longitudinally of the stock and are substantially square in cross section. The ribs 29 and 30 are equal in length to the grooves 16, so that, when the blades are in 30 normal expanded position, their upper ends will engage against the lower terminal of the member 28, and the lower ends of the ribs 29 and 30 will engage against the horizontal end walls 20 of the grooves 16.

35 Referring now particularly to Fig. 3, it will be seen that, when the blades are applied to opposite sides of the stock, the members 29 and 30 are received within the grooves 16 of the blades, and that by reason 40 of the dove-tailed formation of the grooves and ribs the blades may slide upon the stock without liability of lateral displacement.

In order to permit the vertical sliding movement of the members 10 and 11 on the 45 stock 12, and, at the same time, hold them against displacement from operative position, the members 31 and 32 adjacent their upper terminals are cut-away to produce recesses 34. These recesses 34 are equal in 50 length to the distance through which the blades must slide in order to move the expanding head from the position shown in Fig. 1, in which the blades are spread, to the position shown in Fig. 2, wherein the expanding head 13 is received within the enlarged portions of the recesses 14, permitting the blades to move in toward each other. The strap members 26 are seated in the recesses 34, and obviously, by engagement with 55 the upper and lower walls thereof, limit the sliding movement of the blades of the stock. It will be seen that the straps 26 are positioned somewhat below the upper terminals of the bits so that the lugs or projections 35, 60 which are formed as the result of cutting

the recesses 34, may be positioned between the upper terminals of the blades and against the strap members 26 when the blades of the tool are in spread relation, as shown best in Fig. 1.

70 The expanding head member 13 is, in the preferred embodiment of the invention, formed from a substantially cylindrical block of metal, the lower terminal of which is slightly rounded, as indicated at 36, so 75 that it will ride freely and easily over the walls of the recesses 14. The member 13 is, at its upper end, formed with a bore adapted to receive the terminal of a rod or stem member 36^a. A pin 36^b is inserted through the 80 head for holding the stem against withdrawal. This member 36^a is preferably formed integrally with the stock member 12 and extends downwardly from the approximate center thereof. If so desired, however, 85 the member 36^a may be made separately from the stock 12 and be threaded thereinto. Wound about the member 36^a and bearing at 90 its upper terminal against the upper end of the expanding head 13 is a helical spring 37. 95 The upper terminal of this spring 37 bears against a sleeve 38 which is slidable on the member 36^a and is equipped at its lower terminal with an outwardly extending collar member 39.

95 At diametrically opposite points of the collar member 39 are formed spaced apertured ears 40 and 41 adapted to receive between them the terminals of the pivoted pawls or catch members 42 and 43. These 100 pawl members 42 and 43 are so pivoted that their upper terminals normally tend to swing outwardly into the position shown in Fig. 5. These members 42 and 43 are adapted to be received within the recesses 14, and 105 as a means, therefore, for preventing the sleeve member turning on the stem 36^a, which would result in the displacement of the pawls from the recesses 14, the sleeve is 110 preferably splined on the member 36^a, as indicated at 44.

115 It will be seen upon reference to Fig. 2 particularly, that, when the stock 12 is drawn upwardly to lodge the head 13 in the recesses 14, so that the lower terminals of the blades 10 and 11 may be moved inwardly to permit the passage of the tool through the well casing, the pawls 42 and 43 will engage against the end walls 17 of the recesses, thus holding the spring against upward movement on the stem or rod member 36^a, with the resultant compression of the spring. It is obvious then that as soon as the lower terminals of the blades emerge from the lower 120 end of the wall casing that the spring 37 125 will, by reason of its tendency to expand, force the head member 13 downwardly, separating the cutting members 15 and arranging them in operative relation.

130 The pawls 42 and 43 are pivoted between

the ears 40 and 41 in such manner that when the pawls are engaging the walls 17 of the recesses 14, all weight will be removed from the pivot pins of the pawls, and will be borne by the shoulders 45, which, as shown in Fig. 5, are formed at the lower terminals of these pawl members. Intermediate their length the cutting blades 10 and 11 are enlarged, producing shoulders, indicated at 46. These shoulders are adapted to engage against the well casing when the tool is being withdrawn so that the bits will be held against upward movement until the continued pull on the stock has withdrawn the expanding head 13 into the recesses 14, allowing the cutting members 15 to move inwardly into their normal position. In this connection, it may be well to observe that the blades are made of highly tempered steel, and are, therefore, comparatively resilient. By reason of their resiliency, the blades normally tend to extend in parallel relation to each other, and to engage against the stock 12 throughout the length thereof. It is only when the head member is projected downwardly between the lower ends of the blades that the members 15 are widely separated.

The enlargements or shoulders formed at 46 intermediate the length of the cutting blades merge at their lower portions into the blades, as indicated at 47, so that when the tool is inserted in the upper end of the well casing a gradual inclined surface will be presented to the casing for forcing the members 15 inwardly toward each other. Inasmuch as these shoulders 46 are subjected to unusual wear during the use of the tool, it has been found expedient to provide wear plates or ribs 48. These wear plates or ribs 48 consist in strips of hard steel, which are removably applied to the enlarged portions 46, being insertable in recesses formed therein. The walls of the recesses within which these members 48 are received are inwardly divergent, and serve to hold the wear plates against accidental displacement by engagement with the divergent edges 49 of the plates.

In reduction to practice, it has been found that the form of this invention, illustrated in the drawings and referred to in the above description as the preferred embodiment, is the most efficient and practical; yet realizing that the conditions concurrent with the adoption of this device will necessarily vary, it is desirable to emphasize the fact that various minor changes in details of construction, proportion and arrangement of parts may be resorted to, when required, without sacrificing any of the advantages of this invention, as defined in the appended claims.

What is claimed is:

1. An under-reamer including a stock, co-

acting bit members slidable on the stock, and an expanding head removably attached to the stock in position between the bit members for normally holding the cutting terminals of the bit members in expanded operative relation. 70

2. An under-reamer including a stock, co-acting bit members slidable on the sides thereof, means limiting the sliding movement of the bit members, an expanding head member removably secured to the stock and positioned between the lower terminals of the bit members, and yieldable means for normally holding the head member in operative position between the lower terminals 75 80

3. An under-reamer including a stock, co-acting bit members slidable thereon, means carried by the bits and engageable with the stock for limiting the sliding movement of the bit members, an expanding head member removably secured to the stock and positioned between the lower terminals of the bit members, and yieldable means for normally holding the head member in operative 85 90 position between the lower terminals of the bit members, whereby the cutting terminals of the bit members are held in expanded operative relation.

4. An under-reamer including a stock member having longitudinally extending ribs and recesses at the upper ends of the ribs, a pair of co-acting bit members slid- 95 able on the stock and having recesses receiv- ing the ribs thereof, straps connecting the bits at their upper terminals, said straps being movable through the recesses formed in the opposite faces of the stock, the terminals of the recesses being engageable by the straps, whereby the sliding movement of the bits is limited, and a spring - pressed head member adapted to normally hold the lower cutting terminals of the bits in ex- 100 105 panded relation.

5. An under-reamer including a stock member, co - acting bits slidable thereon, means for limiting the movement of the bits, an expanding head, a rod extending down- 110 115 wardly from the stock and having its lower terminal threaded to receive the head, a spring wound about the rod and bearing at its lower terminal against the head, means carried by the rod and engaging the adja- 120 cent faces of the bits, said means acting as a stop for the upper terminal of the spring, whereby the head member is normally held in position between the lower terminals of the bits for holding the cutting edges there- of in operative expanded relation.

6. An under-reamer including a stock member, co-acting bits slidable thereon, means formed integrally with the stock and engaging the bits for holding the bits against lateral movement, means for limiting the sliding movement of the bits, each of said 125 130

- bits having a recess formed in its inner face adjacent its lower end, the lower terminals of the recesses merging into the inner faces of the bits, a head member arranged for 5 sliding movement in the said recesses, and yieldable means for normally holding the head between the lower terminals of the bits, whereby the cutting edges of the bits are held in operative expanded relation.
- 10 7. An under-reamer including a stock member, co-acting bits slidable thereon, means for limiting the sliding movement of the bits, each of said bits having a recess formed in its inner face adjacent its lower 15 end, the lower terminals of the recesses merging into the inner faces of the bits, a head member arranged for sliding movement in the said recesses, a helical spring bearing at its lower terminal against the head, and 20 means engaging the upper terminal of the spring and also engaging in the recesses of the bits for holding the spring against upward movement, said spring normally holding the head between the lower terminals of 25 the bits, whereby the cutting edges of the bits are held in operative expanded relation.
8. An under-reamer including a stock, a pair of co-acting bit members slidable thereon, means for limiting the sliding movement 30 of the bits, each of said bits having an elongated recess formed in its inner face, the lower ends of the recesses merging into the face of the bit adjacent the lower terminal thereof, a rod extending downwardly from 35 the stock, a head member mounted on the lower terminal of the rod and adapted to be received within the recesses of the bits, a helical spring wound about the rod and bearing at its lower terminal against the 40 head member, a sleeve slidable on the rod and bearing against the upper terminal of the spring, and a pair of pawl members pivotally attached to the sleeve and adapted to normally seat in the recesses of the bit members, whereby the upward movement of the 45 stock between the bits will compress the spring for automatically moving the stock again downwardly between the bits and for moving the head member into expanding po-
- sition between the lower terminals of the 50 bits when the stock is released.
9. An under-reamer including a stock member, longitudinal ribs formed thereon, bits provided on their inner faces with longitudinal channels receiving the ribs whereby 55 the bits are slideable longitudinally on the stock, strap members carried by the bits and connecting the upper terminals thereof, said strap members being engageable with the stock for limiting the sliding movement of 60 the bits, and means normally holding the edges of the bits in operative expanded relation.
10. An under-reamer including a stock provided on its opposite faces with longitudinally extending ribs and having longitudinally extending recesses formed in its opposite faces, bit members engaging against the sides of the stock and provided with longitudinal channels on their inner faces, 70 the said channels receiving the ribs whereby the bits are slideable on the stock and are held against lateral movement with respect thereto, straps connecting the upper terminals of the bits, the said straps having their 75 intermediate portions seated in the recesses of the stock and being engageable with the stock for limiting the sliding movement of the bits, and spring-pressed means normally holding the cutting edges of the bits in operative extended relation.
11. An under-reamer including a stock, coacting bits slidable thereon, an expanding head carried by the lower terminal of the stock and rigid with respect thereto, a slideable member interposed between the head and stock, and yieldable means normally holding the slideable member in engagement with the bits whereby the head is normally held in position to maintain the cutting 90 edges of the bits in operative expanded relation.

In testimony whereof I affix my signature in presence of two witnesses.
